CROSS COMPOUND TURBINE

Filed June 15. 1931

Inventor:
John H. Doran,
Chas. W. Mullar
by His Attorney.

UNITED STATES PATENT OFFICE

JOHN H. DORAN, OF SCHENECTADY, NEW YORK, ASSIGNOR TO GENERAL ELECTRIC COMPANY, A CORPORATION OF NEW YORK

CROSS COMPOUND TURBINE

Application filed June 15, 1931. Serial No. 544,405.

The present invention refers to cross compound turbines in which the elastic fluid produced in a generator is supplied to the inlet of a high pressure turbine part and the exhaust of said high pressure turbine part is supplied to a low pressure turbine part.

In connection with the operation of such turbines, the condition obtains sometimes that the turbines are operated at no load, and under these circumstances it is required that cooling medium such as elastic fluid be supplied to the turbines to keep down the temperature of the rotor. Otherwise, due to friction the rotor would become over-heated. An instance wherein such turbines are operated at no load is met with when a turbo-generator is floated on the line, the generator acting as a synchronous condenser.

The object of my invention is to provide an improved construction and arrangement for supplying cooling medium to a cross compound turbine for protecting it, and particularly for protecting the low pressure part, against over-heating when the turbine is running idle.

This is accomplished according to my invention by the provision of certain protective means actuated in response to conditions in the supply conduit to the low pressure part and adapted to cause live steam to be supplied directly to said low pressure part if, for instance, the steam pressure in said supply conduit decreases beyond a minimum value.

For a consideration of what I believe to be novel and my invention, attention is directed to the following description and the claims appended thereto.

In the drawing, the figure shows a cross compound turbine installation, partly diagrammatic and partly in cross section, embodying my invention.

Referring to the drawing, 1 and 2 represent the high and low pressure parts of a cross compound turbine, in the present instance shown as being arranged on separate shafts and adapted to drive electric generators 3 and 4 respectively. 5 is an elastic fluid generator which supplies fluid through a conduit 6 to the high pressure part 1 of the turbine. 7 represents a reheat which is connected to the exhaust conduit of the high pressure part and which supplies the re-heated elastic fluid through a conduit 8 to the low pressure part 2 of the turbine. 9 is

a manually operated main valve provided in conduit 6 for shutting off the steam supply to the high pressure part. 10 is another valve means provided in said conduit and actuated automatically, in the present instance shown by a speed responsive governor 11 provided on the right end of a lever 12 and being adapted to control a fluid actuated motor 13 comprising a pilot valve 14 having its valve disks connected by a stem 15 to said lever 12, and a cylinder 16. Provided in cylinder 16 is a piston 17 having its stem 18 connected to the left end of lever 12 and being adapted to control valve means 10. The operation of this fluid actuated motor which is known in the art is briefly as follows: Increase of speed of the turbine causes the weights 19 of the regulator to fly outwardly and thus causes an upward movement of the right end of lever 12 and a corresponding upward movement of the pilot valve to the effect that oil or like liquid is supplied to the upper part of cylinder 16 and drained off from the lower part of this cylinder. This causes downward movement of piston 17 and accordingly a closing actuation of valve means 10. The downward movement of piston 17 also effects a corresponding movement of the pilot valve whereby the latter is restored to its original position.

Provided in conduit 8 is another valve means 20 for regulating the supply of fluid to the low pressure part. The control of this valve means is in the present instance shown as being accomplished in a way similar to that described above, that is, by a speed responsive governor 21 which is adapted to regulate a fluid actuated motor 22 comprising a pilot valve 23 and a cylinder 24.

The arrangement so far described may be considered as typical for any cross compound turbine installation in which the two parts are arranged on different shafts.

In order to prevent overheating of the turbine bucket wheels if the supplied steam reaches a minimum value, that is, if valve means 10 is near its closed position I provide a by-pass 25 around the fluid admission controlling valve 10. This by-pass allows a certain amount of steam to be supplied to the high pressure part irrespective of the position of valve means 10 and thus prevents overheating of the bucket wheels, at least of said high pressure part. This amount of steam, however, may be insufficient to prevent

overheating of the low pressure part, particularly if the exhaust of the high pressure part is passed through a re heater 7 and has a long path until it reaches the low pressure part.

In order to successfully prevent overheating of the low pressure part I may provide according to my invention a conduit 26 connected to the live elastic fluid line 6 and 10 adapted to admit under certain conditions live elastic fluid directly from the elastic fluid generator to the low pressure part. 27 represents a valve means which in the present instance I have shown as being actuated by 15 pressure responsive means 28 connected to the admission conduit 8 of the low pressure part and comprising a casing 29 in which is provided a diaphragm connected to stem 30 of valve 27. The upper part of casing 29 20 has a pipe 31 connected to supply conduit 8. A spring 32 provided between the diaphragm and the lower half of casing 29 biases the valve towards open position.

The operation of my arrangement is as 25 follows: Under normal conditions, valve 27 is closed. By "normal conditions" I mean conditions under which sufficient elastic fluid is conducted from the high pressure part to the low pressure part 2 to prevent excessive 30 heating of the low pressure part. If the cross compound turbine is running at low load, particularly if the generators are operating as synchronous condensers, that is, when the pressure in conduit 8 decreases be- 35 yond a predetermined value, it will cause a corresponding decrease in the upper part of the pressure responsive device 28 to the effect that the diaphragm of this device moves upwardly under action of the spring 32 and 40 effects opening of valve means 27. The opening of this valve permits a sufficient amount of fluid to be supplied from the elastic fluid generator directly to the low pressure part of the turbine whereby over-heating of this 45 part is prevented.

If now the load increases again it will cause a corresponding increase in pressure in the upper part of the pressure responsive device 28 to the effect that the latter causes a closing 50 actuation of valve 27.

In accordance with the provisions of the patent statutes I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States, is:

1. The combination with a cross compound turbine comprising a high pressure part and a low pressure part, of an elastic fluid generator for supplying elastic fluid to said high pressure part, a valve means for regulating

the admission of elastic fluid to said high pressure part, a by-pass around said valve means to admit a minimum amount of elastic fluid to said high pressure part for protecting said part against over-heating, a conduit 70 for passing the exhaust steam of the high pressure part to said low pressure part, the exhaust of the high pressure part being normally sufficient to prevent excessive heating of the low pressure part, a conduit connecting the inlet of said low pressure part directly to said fluid generator, a normally closed valve means in said last named conduit, and a device responsive to the fluid pressure in the conduit for opening said last named valve 75 means to permit the supply of live elastic fluid to the low pressure part whereby overheating thereof is prevented.

2. The combination with a cross compound turbine installation comprising a high pressure turbine part and a low pressure turbine part, of an elastic fluid generator, a conduit connecting said elastic fluid generator with said high pressure part, a valve means in said conduit for regulating the admission of elastic fluid to said high pressure part, a by-pass connected to said conduit around said valve means for admitting a certain amount of fluid to said high pressure part for protecting the high pressure part against overheating at low load and while running idle, a re-heater and a conduit provided between the exhaust of said high pressure part and the inlet of said low pressure part, another valve means provided in said conduit for regulating the admission of elastic fluid to said low pressure part, a conduit for supplying live elastic fluid directly to said low pressure part, a valve means in said last named conduit, and a pressure responsive device for actuating said last named valve means in terms of fluid pressure supplied through said other valve means to said low pressure part whereby overheating of the latter is prevented.

3. The combination with a cross compound turbine installation comprising a high pressure and a low pressure part, of an elastic fluid generator for supplying elastic fluid to said turbine, valve means for controlling the supply of elastic fluid to said high pressure part, a re-heater and a conduit for supplying the exhaust elastic fluid of said high pressure part to said low pressure part, and means for preventing overheating of the low pressure part comprising a conduit for supplying live elastic fluid directly from said elastic fluid generator to said low pressure part, and a pressure responsive device for actuating said last named valve means in terms of pressure of elastic fluid supplied through said re-heater and said conduit to said low pressure part.

In witness thereof, I have hereunto set my hand,

JOHN H. DORAN.
